E. MAHADEEN

Des. 109,664

LACE MEDALLION

Filed March 4, 1938

Inventor:

Eli Mahadeen

UNITED STATES PATENT OFFICE

109,664

DESIGN FOR A LACE MEDALLION

Elik Mahadeen, Jersey City, N. J.

Application March 4, 1938, Serial No. 75,579

Term of patent 3½ years

To all whom it may concern:

Be it known that I, Elik Mahadeen, a citizen of the United States, residing at 3711 Hudson Boulevard, in the county of Hudson and State of New Jersey, have invented a new, original, and ornamental Design for a Lace Medallion, of which the following is a specification, reference being had to the accompanying drawing, forming a part thereof.

The accompanying drawing shows a lace medallion embodying my design.

I claim:

The ornamental design for a lace medallion as shown.

ELIK MAHADEEN.
